US00D548621S

(12) **United States Design Patent** (10) **Patent No.:** **US D548,621 S**
Assuncao et al. (45) **Date of Patent:** **** Aug. 14, 2007**

(54) **CLOCK**

(76) Inventors: **Eduardo Antonio Assuncao**, 15072 Ashland Pl., #133 D, Delray Beach, FL (US) 33484; **Cristiane Rocha Assuncao**, 15072 Ashland Pl., #133 D, Delray Beach, FL (US) 33484

(**) Term: **14 Years**

(21) Appl. No.: **29/254,049**

(22) Filed: **Feb. 16, 2006**

(51) LOC (8) Cl. **10-01**

(52) U.S. Cl. **D10/2; D10/10; D10/14**

(58) Field of Classification Search **D10/1-29; 368/276-278, 285, 316, 317, 10, 223, 21-27**
 See application file for complete search history.
